PARTY CONFECTIONERY BASKET

Sara Rae Naimon, Milwaukee, Wis.

Application March 12, 1956, Serial No. 40,568

Term of patent 14 years

(Cl. D58—4)

Fig. 1.

Fig. 2.

Fig. 3.

Fig. 4.

The side not shown is the same as the side shown.

I claim:

The ornamental design for a party confectionery basket, as shown and described.
